ELECTRIC SIGNALING SYSTEM.

1,393,443.

Specification of Letters Patent. Patented Oct. 11, 1921.

Application filed April 14, 1917. Serial No. 161,948.

To all whom it may concern:

Be it known that I, ROBERT J. HEWETT, a citizen of the United States, and a resident of Westfield, county of Union, and State 5 of New Jersey, have invented certain new and useful Improvements in Electric Signaling Systems, of which the following is a specification, reference being had to the accompanying drawings, which form a part 10 hereof.

This invention relates to an improved signaling system especially adapted for use in connection with single track railway lines over which traffic proceeds in both directions. 15 Its most important present utility is in connection with stretches of single track between passing sidings, although the invention is not limited to this particular use.

In the accompanying drawings forming 20 part of this specification, the circuits and connections of a complete absolute-permissive system between passing sidings of a single track are shown in diagram, Figure 1 and Fig. 2 each showing one-half of the 25 entire arrangement.

Figs. 1 and 2 taken together show a complete absolute-permissive block signal system extending from east-bound absolute signal 10 at passing station W on the left 30 of Fig. 1 to west-bound absolute signal 15 at passing station X on the right of Fig. 2. It includes east-bound signals 10, 12 and 14 for controlling east-bound train movements; and also west-bound signals 15, 13 and 11 35 for controlling west-bound train movements.

West-bound signal 9 at passing station W controls west-bound train movements into passing station W and east-bound signal 16 at passing station X controls east- 40 bound train movements into passing station X. Signals 9 and 16 are station signals.

The track is divided into a suitable number of track zones, T⁹ to T¹⁶ inclusive, properly insulated from one another. Each of 45 these zones is provided with track batteries, indicated at TB¹⁰ to TB¹⁶ inclusive in the drawings. (For clearness, the track batteries for the end sections are omitted.)

The control circuits are of the polarized 50 type in which a neutral-polar line relay controls the two movements of the signal arm as the 45° and the 90° movements. All of these line relays, except L¹⁴, for the stretch between the passing stations are of the slow 55 release type, as indicated by the black shading at their poles. But relays L⁸—not

shown—L⁶ and L⁹ for the signals governing the entrance to the passing stations are of the ordinary type and are not slow release. At signal 14 the slow release is effected by circuit controller K instead of by relay L¹⁴, as will be hereinafter explained. All signals are shown as standing normally at 90° position. The zero position of the signal arm indicates stop, the 45° position 60 indicates proceed at caution and the 90° position indicates proceed at speed. The last two positions, therefore, indicate proceed.

All the east-bound control circuits are numbered and only part of the west-bound 70 similar reference numerals being employed for similar circuits associated with the several signals. East-bound absolute signal 10 is controlled by east-bound neutral-polar line relay L¹⁰, the circuit is as follows: from line relay L¹⁰, wire 20, contact 21 of track relay R¹⁰, line wire 22, contact 23 of track relay R¹¹, wire 24, contact 25 of east-bound polar selector relay S¹², wire 26, wire 27, positive pole changer P, wire 28, wire 29, 75 wire 30, battery MB¹², wire 31, wire 32, negative pole changer N and the common wire C back to east-bound line relay L¹⁰.

Pole changers P and N of signal 12 move together and are operated by the motor 80 operating mechanism of signal 12. The other pole changers P and N operate in a similar manner with respect to their signals. When signal 12 is in its 45° or its 90° position the pole changers P and N will be in 85 the position shown and a current of normal direction will flow from battery MB¹², through the circuit just traced, and control relay L¹⁰ will be energized at the normal polarity and will hold closed its polar contact 52, and will also hold closed its neutral contacts 48 and 41. Neutral contact 48 controls the 45° motor mechanism through 90 the local circuit as follows: from positive terminal of battery MB¹⁰, wire 30, wire 29, wire 47, contact 48, wire 49 to the 45° motor mechanism of signal 10, wire 50, wire 32, wire 31, to the negative terminal of battery MB¹⁰. This motor circuit moves the 95 signal 10 from its zero or stop position to the 45° position. Contact 48 and polar contact 53 control the 90° motor circuit which is as follows: from the positive terminal of battery MB¹⁰, wire 30, wire 29, wire 47, contact 48, wire 51, polar contact 52, wire 53, contact 54, and wire 55 to the 90° motor mechanism of signal 10, wire 50, wire 32,

100
105
110

and wire 31 to the negative terminal of battery MB^{10} . This 90° motor mechanism moves the signal from 45° to the 90° position. When signal 12 is in its zero or stop position its pole changers P and N will be reversed, that is, thrown to the left, and this reverses the polarity of battery MB^{12} with respect to the line and a current of reverse direction will flow from battery MB^{12} through the line wire 22 and control relay L^{10} , and the latter will be energized with a reverse polarity which will throw its polar contact 52 to the left and open the 90° motor circuit of signal 10, and signal 10 will be held in its 45° position only.

This polarized control circuit is shown as being a simple, cheap, and generally acceptable control circuit. The usual type of control by means of two separate control wires, "home" and "distant," may be used although the former is preferred. The neutral polar control relays L^{12} and L^{14} are energized, respectively, from batteries MB^{14} and MB^{16} by similar circuits indicated by similar reference numerals.

In tracing the foregoing line control circuit of relay L^{10} it will be noted that it goes through a contact 25 of east-bound polar selector relay S^{12} . This polar selector relay S^{12} is one of the new and important features of the invention and will now be explained.

East-bound polar selector relay S^{12} is normally energized and is included in a normally closed local circuit controlled by contact 41 of east-bound line relay L^{12} and also by a pair of pole changing contacts 37 and 43 of track relay R^{12} . The normal circuit is as follows: from positive terminal of battery MB^{12} , wire 30, wire 36, front contact 37, wire 38, wire 39, east-bound polar selector relay S^{12} , wire 40, contact 41 of east-bound line relay L^{12} , wire 42, front contact 43, wire 44, and wire 31 to the negative terminal of battery MB^{12} . This normal current will energize east-bound polar selector relay S^{12} with a normal polarity and its polar contact 34 will be held to the left or open position as shown. When track relay R^{12} is deenergized its front contacts 37 and 43 will be open and its back contacts 45 and 46 will be closed and this will reverse the polarity of battery MB^{12} with respect to the east-bound polar selector relay S^{12} as follows: from the positive terminal of battery MB^{12} , wire 30, wire 36, back contact 45, wire 42, contact 41, wire 40, polar selector relay S^{12} , wire 39, back contact 46, wire 44, wire 31, to the negative terminal of battery MB^{12} . This reverse current will reverse the polarity of polar selector relay S^{12} and it will throw its polar contact 34 to the right or closed position.

At east-bound signal 14 the polar selector relay S^{14} is shown as controlled by similar pole changing contacts 37, 43, 45 and 46, and

also the circuit controller K on the signal instead of the contact 41 on the line relay L^{14} . Its circuit is as follows: from positive terminal of battery MB^{14} , wire 30, wire 36, front contact 37, wire 38, wire 39, polar selector relay S^{14} , wire 40, contact segment I and arm K operated by signal 14, wire 42, front contact 43, wire 44, wire 31, to the negative terminal of battery MB^{14} . Circuit controller K follows the movement of the semaphore arm and is closed when the arm moves from the 45° to 90° position and from 90° down to the 45° position, but will be open when the arm is below the 45° position. Circuit controller K has the same control on polar selector relay S^{14} as contact 41 of the line relay L^{14} would have, and is shown merely to indicate an alternative way for controlling the polar selector relay.

The line control circuit for neutral-polar line relay L^{14} is as follows: from relay L^{14} , wire 20, contact 21 of track relay R^{14} , line wire 22, contact 23, wire 24, positive pole changer P, wire 28, wire 29, battery MB^{16} , wire 32, negative pole changer N and the common wire back to line relay L^{14} . This circuit is similar to the circuits for relays L^{10} and L^{12} but it has no selective control at signal 16. This is due to the fact that it is the last circuit in the east-bound absolute control series. The polar selector relays, such as S^{12} and S^{14} , and their circuits therefore are omitted in connection with line relay L^{16} . At signal 10 the polar selector relay S^{10} is energized from battery MB^{10} through circuit connections similar to those for relays S^{12} and S^{14} and are indicated by similar reference numerals.

The operations of the east-bound absolute control circuits when actuated by a west-bound train, may now be explained. A west-bound train at passing station X, on entering track section T^{15} will deenergize track relay R^{15} and its contact 23 will open the east-bound line control circuit of line relay L^{14} and deenergize this relay which, by opening its contact 48, will put signal 14 to danger and this, by opening its circuit controller K, will open the local selector circuit and deenergize polar selector relay S^{14} and its neutral contact 25 will open the next east-bound control circuit to the west and deenergize line relay L^{12} which by opening its contact 48 will put signal 12 to danger. Relay L^{12} , by opening its contact 41, will deenergize polar selector relay S^{12} and its neutral contact 25 will open the next east-bound control circuit to the west and deenergize line relay L^{10} , and put absolute signal 10 to danger. The entry of the west-bound train into track section T^{15} , therefore, by this repeating arrangement of the line relays and polar selector relays, will put all east-bound signals to danger and the stop position of east-bound absolute signal 10 will hold the

route for the west-bound train. It will be noted that the neutral contacts 25 of the polar selector relays are active in this repeating action. The polar contacts 34 remain in their normal or open position during such repeating action, and are only closed during east-bound train movements, as will be explained farther on.

From the foregoing it will be seen that 10 absolute signal 10 is the first of the series of east-bound absolute controlled signals. This absolute control is due to the repeating arrangements of the several line relays and the local polar selector relays as previously explained, to-wit, line relay L^{12} and local polar selector relay S^{12} at signal 12 and line relay L^{14} and local polar selector relay S^{14} at signal 14. Signal 14 is the last of the east-bound series.

20 The principle involved in the absolute control may be stated more briefly by saying that each line control circuit repeats back to the next line control circuit in the rear, these circuits being thus relayed together 25 from east to west.

At east-bound absolute signal 10, it will be noted that the polar selector relay S^{10} does not control any line circuit by its neutral contact 54. The reason for this is that 30 the absolute control ends at signal 10. Control relay L^{10} by its contact 41 controls the polar selector relay S^{10} as usual, but the neutral contact 54 of polar selector relay S^{10} does not control the east-bound signal 8 in 35 the rear—not shown. Instead of this it controls the 90° motor mechanism of signal 10, being included in the circuit with wire 53, contact 52 of relay L^{10} as will be understood.

The east-bound signal to the west of signal 10 is signal 8—not shown—located at the west end of passing station W, and corresponds to signal 16 at the west end of passing station X in Fig. 2. The control circuit for east-bound signal 8 is only partly 40 shown, and beginning with the line wire is as follows: from line wire 22, contact 23 of track relay R^8 , wire 24, contact 25' of track relay R^{10} , wire 26', wire 27, positive pole changer P, wire 28, wire 29, wire 30, positive terminal of battery MB^{10} , wire 31, wire 32, negative pole changer N and the common wire C back to the line control relay for east-bound signal 8, then through contact 21 of track relay R^8 —not shown—and 45 to line wire 22. The latter part of this circuit is the same as the similar part of the circuit for line relay L^{16} shown in Fig. 2. A west-bound train in track section T^{16} will deenergize track relay R^{10} and its contact 25' will open the control circuit for signal 8 and puts it at danger. Contact 50 55 60 65 70 75 80 85 90 95 100 105 110 115 120 125 130 25' of track relay R^{10} , therefore, gives signal 8, for a west-bound train, an overlap control into track section T^{10} . This is advantageous because it gives safe protection

to two opposing trains entering passing station W. An east-bound train in track section T^{10} will put signal 8 to 45° position, as will appear from the following explanations.

The full performance of the circuits will now be explained, assuming that everything is normal, by considering the movement of two following east-bound trains entering into the block through passing station W.

As the first train enters track section T^8 75—not shown—it deenergizes track relay R^8 —not shown—and by opening its contact 21,—not shown—puts signal 8 to danger behind the train, in the same way as an east-bound train entering track section T^{16} would 80 operate on relay R^{16} and signal 16. As this first train enters track section T^9 it deenergizes its track relay R^9 and by opening its contact 23 continues signal 8 at danger.

When the train enters track section T^{10} 85 track relay R^{10} will be deenergized. This causes contacts 45 and 46 to close and reverse the polarity of current from battery MB^{10} through polar selector relay S^{10} . It also opens at contact 21 the circuit through line 90 relay L^{10} . Relay L^{10} is of the slow release type, as has heretofore been explained, so that before it drops its contacts 48 and 41, the reverse current through relay S^{10} has closed its polar contact 34. When now relay L^{10} 95 drops its contacts 48 and 41, signal 10 moves to stop position thereby shifting the position of pole changers P and N and the circuit through polar relay S^{10} is broken at contact 41. As soon as pole changers P and N reverse their position, a current of reverse polarity flows from battery MB^{10} through the line circuit of line relay L^8 . This circuit is as follows: from positive terminal of battery MB^{10} , through wires 30 and 29, positive pole changer P, common wire C, line relay L^8 , contact 21 of track relay R^8 , wire 22, contact 23 of track relay R^9 , wires 24 and 33, polar contact 34, now closed, wires 35 and 37, negative pole changer N, wire 32 to 100 negative pole of battery MB^{10} . This reverse current energizes line relay L^8 with a current of reverse polarity and thereby closes neutral contact 48 of relay L^8 and opens its polar contact 52. This closes the 105 local circuit from battery MB^8 through the 45° motor mechanism of signal 8 and puts this signal to 45° position. The following east-bound train is then permitted to enter the passing station W at signal 8. The 110 polar contact 34 of selector relay S^{10} remains closed after said relay is deenergized because of the biased permanent magnetic condition due to its structure. Such polar contact, like the polar contacts of the other 115 polar relays shown in the drawings, always remains in the position to which it has been thrown by its last controlling current and is not affected by a discontinuance of said current.

When the first east-bound train clears out of track section T^{10} and enters track section T^{11} , track relay R^{10} will be energized and its contacts 25 and 21 and its pole changing contacts 37 and 43 will be closed; but the deenergized condition of control relay L^{10} , due to the break in its circuit at contact 23 of track relay R^{11} , (which has now been deenergized) and the open condition of its neutral contact 41 will still hold open the local circuit for polar selector relay S^{10} and its polar contact 34 will remain closed.

As the first east-bound train enters track section T^{12} and clears out of track section T^{11} , track relay R^{12} will be deenergized. This breaks at contact 21 the circuit of line relay L^{12} . It also closes pole changing contacts 45 and 46 thereby reversing the local current from battery MB^{12} through relay S^{12} and closing polar contact 34. The slow release of relay L^{12} permits this action of polar relay S^{12} to take place before contact 41 opens. Thereafter, relay L^{12} opens its contacts 48 and 41. The break at contact 48 puts signal 12 to stop position behind the train and reverses pole changers P and N. The break at contact 41 opens the circuit through polar relay S^{12} . The reversal of pole changers P and N of signal 12 throws a current of reverse polarity on the circuit of line relay L^{10} which may be traced as follows: from positive pole of battery MB^{12} , through wires 30, 29 and 28, positive pole changer P, common wire C, line relay L^{10} , wire 20, contact 21, wire 22, contact 23, wires 24 and 33, polar contact 34, wires 35 and 27, negative pole changer N and wires 32 and 31 to negative pole of battery MB^{12} . Line relay L^{10} is therefore energized by a current of reverse polarity whereby it closes its contacts 48 and 41 and opens its polar contact 52. The closing of contact 41 energizes polar relay S^{10} and closes contact 54 and opens polar contact 34. The closing of neutral contact 48 and the opening of polar contact 52 closes the circuit through the 45° motor mechanism of signal 10 whereupon this signal moves to its 45° position. This also moves pole changers P and N of signal 10 back to normal position whereupon current in normal direction from battery MB^{10} is thrown upon the line circuit of line relay L^8 . This closes polar contact 52 of relay L^8 thereby closing the 90° motor circuit of signal 8 whereupon this signal moves to its 90° position. When the train enters track section T^{13} , it breaks at contact 23 of track relay R^{13} the line circuit of line relay L^{12} previously broken at contact 21 of track relay R^{12} and continues signals 10 and 12 in the same positions last described. When the train enters track section T^{14} and clears out of track section T^{13} , signal 14 moves to stop position and its pole changers P and N are reversed. This reverses the current through line relay L^{12} and

moves signal 12 to 45° position and restores its pole changers P and N to normal. Current of normal polarity thereupon flows from battery MB^{12} through line relay L^{10} , thereby closing polar contact 52 and moving signal 10 to 90° position. The circuits and connections for signal 10, as well as this signal, are now all restored to normal condition. The action of the train when entering track section T^{14} upon the circuits and connections whereby signal 14 is put to stop position and signal 12 to 45° position will be understood from what has heretofore been stated, being similar to the action produced by the entry of the train in track section T^{12} . There is, however, a slight difference in the arrangement for controlling polar relay S^{14} . Polar relays S^{10} and S^{12} are controlled by contact 41 of their respective line relays L^{10} and L^{12} . In the case of polar relay S^{14} , instead of controlling this relay by contact 41, it is controlled by a circuit controller K which moves with the signal blade of signal 14. The operation of circuit controller K has heretofore been explained and the circuit which it controls has heretofore been traced.

When the train enters track section T^{15} , it breaks at contact 23 of track relay R^{15} the line circuit of control relay L^{14} and continues signals 14 and 12 in the same positions already described. When the train clears out of track section T^{15} and enters track section T^{16} , it breaks at contact 21 of track relay R^{16} the line circuit of control relay L^{16} thereby putting signal 16 to stop behind the train, as will be understood. When signal 16 has gone to stop position, its pole changers P and N will be reversed, thereby putting a current of reverse polarity from battery MB^{16} on the line circuit of line relay L^{14} . This closes the neutral contact 48 of line relay L^{14} and opens its polar contact 52 thereby moving signal 14 to 45° position. Pole changers P and N of signal 14 are thus restored to normal position so that a normal current is put on the line circuit of line relay L^{12} thereby closing polar contact 52 of relay L^{12} and moving signal 12 to 90° position.

West-bound signals 15, 13, 11 and 9 are provided with circuits similar to those heretofore described with respect to the east-bound signals and operate in the same way. The circuits for signals 13 and 11 have the same reference numerals as have the corresponding circuits of the east-bound signals. The operation of the west-bound signals and their circuits will be readily understood from the explanations heretofore made and need not be specifically described.

It will be noted that when an east-bound train is in track sections T^{12} or T^{13} that signal 10 moves from stop indication to 45° position, whereas, when a west-bound train oc-

- cupies track sections T^{12} or T^{13} , signal 10 is caused to indicate stop. Signal 10 is caused to indicate stop, of course, when a west-bound train enters track section T^{15} and until such train has passed west of signal 10. East and west-bound trains have a similar action upon signals 12 and 14. Likewise, west-bound and east-bound trains have a similar action upon the west-bound signals.
- 10 The action whereby an east-bound train, for example, in a track zone such as T^{12} and T^{13} , east of signal 10, is prevented from causing signal 10 to indicate stop, is due to the action of the polar contact 34 at signal 12 which closes the line circuit of line relay L^{10} when the east-bound train enters such track zone T^{12} and T^{13} .
- 15 It will also be noted that an east-bound train deenergizes the line relays L^{11} , L^{13} and L^{15} of the west-bound signals, the circuits of these relays being relayed together from west to east. Furthermore, it will be noted that although the east-bound train reverses the polarity of the polar selector relays of the 20 east-bound signals, such as relay S^{10} , and closes its polar contact 34, nevertheless the east-bound train does not reverse the polarity of the polar relays of the west-bound signals, such as relay S^{11} , nor close its polar contact 34. For example, when the east-bound train is in track section T^{11} and deenergizes track relay R^{11} , it closes the polar contacts 25 and 26 of polar relay S^{11} , but this relay had been previously deenergized 25 by the opening of its contact 41 when the circuit of line relay L^{11} was opened by the train at contact 23 of track relay R^{10} , and this was continued by the opening of contact 21 at track relay R^{11} . When this east-bound 30 train clears out of track section T^{11} , relay R^{11} closes its pole changing contacts 37 and 43 and also closes at its contact 21 the circuit of relay L^{11} . This closes contact 41 of relay L^{11} and normal current flows through 35 relay S^{11} from battery MB^{11} and polar contact 34 of relay S^{11} remains in its normal open position. All the polar contacts 34 have a corresponding operation.
- 40 Among the advantages of the invention, as described in the foregoing, it may be noted that in certain absolute-permissive signal systems, as heretofore designed, the selective or directional control is effected by picking up a normally deenergized selector relay.
- 45 There is nothing in such arrangement that will give a continuous indication as to the working condition of said selector relay. The normally energized polarized selector relay, as involved in this invention, always 50 controls either the absolute control circuit or a motor circuit so that, in case the local circuit for the polarized selector relay should fail and leave it deenergized, the absolute or repeating control circuit will be 55 left open and the derangement will be

readily apparent by the danger position of the signals involved in the selective control. At signal 10 the failure of the polar selector relay S^{10} will, by the open condition of its neutral contact 54, open the 90° motor circuit and prevent signal 10 from clearing to its 90° position.

70 While the invention has been described and illustrated in the drawings in what is believed to be the best general arrangement for a complete absolute-permissive system between passing stations, various changes may be made therein without departing from the scope of the invention. Furthermore, various features of the invention may be applied to other situations.

75 While this invention is shown in connection with signals standing normally at 90° or safety position, such signals having the well known movable semaphore blade, it will be understood that the invention may be used in connection with other types of signals and which may normally give other indications than that of safety. For example, the system is well adapted for use in 80 connection with light signals.

What I claim is:

1. In a signaling system, a stretch of track; an east-bound signal; means for causing said signal to indicate stop controlled by an east-bound train while said train occupies the stretch extending eastward from the signal up to a certain point; and means for causing said signal to indicate stop controlled by a west-bound train while said train occupies the stretch eastward of the signal up to another point, said means including a control circuit and a polar relay governing said control circuit, said polar relay adapted to close the control circuit by 95 the action of said east-bound train when it has reached a certain point east of said signal and adapted to open the control circuit by the action of said west-bound train when it has reached a point farther east of said signal.

100 2. In a signaling system, a stretch of track; an east-bound signal; means for causing said signal to indicate stop controlled by an east-bound train while said train occupies the stretch extending eastward from the signal up to a certain point; and means for causing said signal to indicate stop controlled by a west-bound train while said train occupies the stretch eastward of the signal up to another point, said means including a control circuit having a normally closed neutral contact and a normally open polar contact in a branch around the neutral contact, and a magnet governing said contacts, said magnet adapted to close the polar contact by the action of said east-bound train when it has reached a certain point east of said signal and adapted to open the neutral contact by the action of 110

said west-bound train when it has reached a point farther east of said signal.

3. In a signaling system, a stretch of track; an east-bound signal; track relays connected with the rails of said stretch and a source of current for each relay; means controlled by a track relay for causing said signal to indicate stop when operated by an east-bound train while said train occupies the stretch extending eastward from the signal up to a certain point; and means controlled by a track relay for causing said signal to indicate stop when operated by a west-bound train while said train occupies the stretch eastward of the signal up to another point, said last mentioned means including a control circuit and a polar relay governing said control circuit, said polar relay adapted to close the control circuit by the action of said east-bound train when it has reached a certain point east of said signal and adapted to open the control circuit by the action of said west-bound train when it has reached a point farther east of said signal.

4. In a signaling system, the combination of a stretch of track; a signal; a control circuit for said signal arranged when closed to cause the signal to give one indication and when open to give another indication; a normally-energized relay having neutral and polar contacts in said circuit; means operable by an east-bound train when it has reached a certain point in said stretch for closing said circuit at one of said contacts; and means operable by a west-bound train when it has reached a point farther east in said stretch for opening said circuit at the other of said contacts.

40 5. In a signaling system, the combination of a stretch of track; a signal; a control circuit for said signal arranged when closed to cause the signal to give one indication and when open to give another indication; a normally-energized relay having neutral and polar contacts in said circuit; means operable by an east-bound train when it has reached a certain point in said stretch for closing said circuit at the polar contact; and means operable by a west-bound train when it has reached a point farther east in said stretch for opening said circuit at the neutral contact.

55 6. In a signaling system, the combination of a stretch of track; a signal; a control circuit for said signal arranged when closed to cause the signal to give one indication and when open to give another indication; a normally-energized relay having neutral and polar contacts in said circuit; means operable by an east-bound train when it has reached a certain point in said stretch for closing said circuit at the polar contact; and means operable by a west-bound train when 60 it has reached a point farther east in said

stretch for opening said circuit at the neutral contact; and means controlled by the west-bound train for continuing to keep said circuit open until the west-bound train has passed west of said stretch of track.

7. In a signaling system, the combination of a stretch of track; a signal; a control circuit for said signal arranged when closed to cause the signal to give one indication and when open to give another indication; neutral and polar contacts in said circuit; means operable by an east-bound train when it has reached a certain point in said stretch for closing said circuit at one of said contacts; and means operable by a west-bound train when it has reached a point farther east in said stretch for opening said circuit at the other of said contacts, both of said means including a normally energized magnet operating directly upon said neutral and polar contacts.

8. In combination, a stretch of track including two adjoining east and west track zones; a signal; a control circuit therefor arranged when open to cause the signal to give one indication and when closed to give another indication; means operable by an east-bound train in the west track zone for opening said control circuit; and means including a normally-energized neutral polar relay controlling said circuit operable by the east-bound train when it has reached a point intermediate the stretch for closing said circuit and operable by a west-bound train in said east track zone for opening said circuit.

9. In combination, a stretch of track including two adjoining east and west track zones; a signal; a control circuit therefor arranged when open to cause the signal to give one indication and when closed to give another indication; means operable by an east-bound train in the west track zone for opening said control circuit; means controlling said circuit operable by the east-bound train when it has reached a point intermediate the stretch for closing said circuit; and means operable by a west-bound train in said east track zone for opening said circuit, said last two means including a normally-energized neutral polar relay controlling said circuit.

10. In combination, a stretch of track including two adjoining east and west track zones; a signal; a control circuit therefor arranged when open to cause the signal to give one indication and when closed to give another indication; a normally-energized relay having neutral and polar contacts in said circuit; means operable by an east-bound train in the west track zone for opening said circuit; means operable by the east-bound train when it has reached a certain point intermediate the stretch for closing said circuit at its polar contact; and means

operable by a west-bound train in the east track zone for opening said circuit at its neutral contact.

11. In combination, a stretch of track including two adjoining east and west track zones; a signal; a control circuit therefor arranged when open to cause the signal to give one indication and when closed to give another indication; a normally-energized relay having neutral and polar contacts in said circuit, the polar contact being in a branch around the former contact; means operable by an east-bound train in the west track zone for opening said circuit; means operable by the east-bound train when it has reached a certain point intermediate the stretch for closing said circuit at its polar contact; and means operable by a west-bound train in the east track zone for opening said circuit at its neutral contact, said last two means including a magnet governing said neutral and polar contacts.

12. In combination, a stretch of track including two adjoining east and west track zones; a signal; a control circuit therefor arranged when open to cause the signal to give one indication and when closed to give another indication; a normally-energized relay having neutral and polar contacts in said circuit; a track relay operable by an east bound train in the east track zone for opening said circuit; a track relay operable by the east bound train when it has reached a certain point intermediate the stretch for closing said circuit at its polar contact; and means operable by a west-bound train in the east track zone for opening said circuit at its neutral contact.

13. In a signaling system, the combination of a stretch of track; a signal; a control circuit for said signal arranged when closed to cause the signal to give one indication and when open to give another indication; a normally-energized relay having neutral and polar contacts in said circuit; a track relay operable by an east-bound train when it has reached a certain point in said stretch for closing said circuit at one of said contacts; and a track relay operable by a west bound train when it has reached a point farther east in said stretch for opening said circuit at the other of said contacts.

14. In a signaling system, a stretch of track comprising adjoining east and west track zones; a signal; track relays and sources of current for the track zones; two control circuits for the said signal controlled by said track relays and relayed together from east to west so that when a track relay of the east track zone is deenergized by a west-bound train both control circuits are opened to cause the signal to indicate stop; a normally-energized relay having a polar contact in the west control circuit; and means operable by an east-bound train when

it has reached a certain point intermediate the stretch for operating said polar contact and thereby preventing said train when in the east track zone from causing the signal to indicate stop.

15. In a signaling system, a stretch of track comprising adjoining east and west track zones; a signal; track relays and sources of current for the track zones; two control circuits for the said signal controlled by said track relays and relayed together from east to west so that when a track relay of the east track zone is deenergized by a west-bound train both control circuits are opened to cause the signal to indicate stop; a normally-energized relay having a neutral contact in the west control circuit through which the control circuits are relayed and a polar contact in the west control circuit in a branch around said neutral contact; and means operable by an east-bound train when it has reached a certain point intermediate the stretch for operating said polar contact and thereby preventing said train when in the east track zone from causing the signal to indicate stop.

16. In a signaling system, a stretch of track; an east-bound signal; means for causing said signal to indicate stop controlled by an east-bound train while said train occupies the stretch extending eastward from the signal up to a certain point; means for causing said signal to indicate stop controlled by a west-bound train while said train occupies the stretch eastward of the signal up to another point, said means including a control circuit and a polar relay governing said control circuit, said polar relay adapted to close the control circuit by the action of said east-bound train when it has reached a certain point east of said signal and adapted to open the control circuit by the action of said west-bound train when it has reached a point farther east of said signal; and a west-bound signal arranged to indicate stop by the action of the east-bound train in any part of the stretch west of the west-bound signal.

17. In a signaling system, a stretch of track; an east-bound signal; track relays connected with the rails of said stretch and a source of current for each relay; means controlled by a track relay for causing said signal to indicate stop when operated by an east-bound train while said train occupies the stretch extending eastward from the signal up to a certain point; means controlled by a track relay for causing said signal to indicate stop when operated by a west-bound train while said train occupies the stretch eastward of the signal up to another point, said last mentioned means including a control circuit and a polar relay governing said control circuit, said polar relay adapted to close the control circuit by the

action of said east-bound train when it has reached a certain point east of said signal and adapted to open the control circuit by the action of said west-bound train when it has reached a point farther east of said signal; and a west-bound signal arranged to indicate stop when any of said track relays west of the west-bound signal is operated by an east-bound train.

18. In a signaling system, the combination of a stretch of track; an east-bound signal; a control circuit for said signal arranged when closed to cause the signal to give one indication and when open to give another indication; a normally-energized relay having neutral and polar contacts in said circuit; means operable by an east-bound train when it has reached a certain point in said stretch for closing said circuit at one of said contacts; means operable by a west-bound train when it has reached a point farther east in said stretch for opening said circuit at the other of said contacts; and a west-bound signal arranged to indicate stop by the action of an east-bound train in any part of the stretch west of the west-bound signal.

19. In combination, a stretch of track including two adjoining east and west track zones; an east-bound signal; a control circuit therefor arranged when open to cause the signal to give one indication and when closed to give another indication; means operable by an east-bound train in the west track zone for opening said control circuit; means including a normally-energized neutral polar relay controlling said circuit operable by the east-bound train when it has reached a point intermediate the stretch for closing said circuit; and operable by a west-bound train in said east track zone for opening said circuit; and a west-bound signal arranged to indicate stop by the action of an east-bound train in any part of the stretch west of the west-bound signal.

20. In a signaling system, a stretch of track comprising adjoining east and west track zones; an east-bound signal; track relays and sources of current for the track zones; two control circuits for the said signal controlled by said track relays and relayed together from east to west so that when a track relay of the east track zone is deenergized by a west-bound train both control circuits are opened to cause the signal to indicate stop; a normally-energized relay having a polar contact in the west control circuit; means operable by an east-bound train when it has reached a certain point intermediate the stretch for operating said polar contact and thereby preventing said train when in the east track zone from causing the signal to indicate stop; a west-bound signal; and east and west control circuits for the west-bound signal controlled

by a train in either track zone and relayed together so that when an east-bound train is in the west track zone both of said control circuits for the west-bound signal will be opened to cause the west-bound signal to indicate stop. 70

21. In a signaling system, a stretch of track; an east-bound signal; track relays connected with the rails of said stretch and a source of current for each relay; means 75 controlled by a track relay for causing said signal to indicate stop when operated by an east-bound train while said train occupies the stretch extending eastward from the signal up to a certain point; means controlled 80 by a track relay for causing said signal to indicate stop when operated by a west-bound train while said train occupies the stretch eastward of the signal up to another point, said last mentioned means including 85 a control circuit and a polar relay governing said control circuit, said polar relay adapted to close the control circuit by the action of said east-bound train when it has reached a certain point east of said signal 90 and adapted to open the control circuit by the action of said west-bound train when it has reached a point farther east of said signal 95 and a west-bound signal arranged to indicate stop when any of said track relays west of the west-bound signal is operated by an east-bound train; and means operable by a west-bound train when it has reached a certain point intermediate the stretch to cause the west-bound signal to indicate proceed. 100

22. In a signaling system, the combination of a stretch of track; an east-bound signal; a control circuit for said signal arranged when closed to cause the signal to give one indication and when open to give another indication; a normally-energized relay having neutral and polar contacts in said circuit; means operable by an east-bound train when it has reached a certain point in 105 said stretch for closing said circuit at one of said contacts; means operable by a west-bound train when it has reached a point farther east in said stretch for opening said circuit at the other of said contacts; a west-bound signal; and east and west control circuits for the west-bound signal controlled by a train in either track zone and relayed together so that when an east-bound train is in the west track zone both of said control circuits for the west-bound signal will be 115 opened to cause the west-bound signal to indicate stop. 120

23. In combination, a stretch of track including two adjoining east and west track zones; an east-bound signal; a control circuit therefor arranged when open to cause the signal to give one indication and when closed to give another indication; means operable by an east-bound train in the west track zone for opening said control circuit; 125 means including a normally-energized neutral polar relay controlling said circuit operable by the east-bound train when it has reached a certain point intermediate the stretch for closing said circuit; and a west-bound signal arranged to indicate stop by the action of an east-bound train in any part of the stretch west of the west-bound signal. 130

- means including a normally-energized neutral polar relay controlling said circuit operable by the east-bound train when it has reached a point intermediate the stretch for 5 closing said circuit; and operable by a west-bound train in said east track zone for opening said circuit; a west-bound signal arranged to indicate stop by the action of an east-bound train in any part of the stretch 10 west of the west-bound signal; and means operable by a west-bound train when it has reached a certain point intermediate the stretch to cause the west-bound signal to indicate proceed.
- 15 24. In a signaling system, a stretch of track comprising adjoining east and west track zones; an east-bound signal; track relays and sources of current for the track zones; two control circuits for the said signal 20 controlled by said track relays and relayed together from east to west so that when a track relay of the east track zone is deenergized by a west-bound train both control circuits are opened to cause the signal 25 to indicate stop; a normally-energized relay having a polar contact in the west control circuit; means operable by an east-bound train when it has reached a certain point intermediate the stretch for operating said 30 polar contact and thereby preventing said train when in the east track zone from causing the signal to indicate stop; a west-bound signal; east and west control circuits for the west-bound signal controlled by a train in 35 either track zone and relayed together so that when an east-bound train is in the west track zone both of said control circuits for the west-bound signal will be opened to cause the west-bound signal to indicate stop; and 40 means operable by a west-bound train when it has reached a certain point intermediate the stretch to cause the west-bound signal to indicate proceed.
- 25 25. In combination, a stretch of track; a 45 signal; a control circuit for the signal; means operable by a west-bound train in any part of the stretch for controlling the control circuit; a normally-energized polar relay; and means controlled by an east-bound 50 train when it has reached a certain point in the stretch for operating the polar relay and thereby preventing said train when it has reached a certain point in the stretch from causing the signal to indicate stop.
- 55 26. In combination, a stretch of track; a signal; a control circuit for the signal; means operable by a west-bound train in any part of the stretch for opening the control circuit and thereby causing the signal to indicate stop; a normally-energized polar relay; and means controlled by an east-bound 60 train when it has reached a certain point in the stretch for operating the polar relay and closing the control circuit and thereby preventing said 65 preventing said train when it has reached a certain point in the stretch from causing the signal to indicate stop.
- 70 27. In combination, a stretch of track; an east-bound signal; a control circuit for the signal; means operable by a west-bound train in any part of the stretch for controlling the control circuit; a normally energized polar relay; means controlled by an east-bound train when it has reached a certain point in the stretch for operating the polar 75 relay and thereby preventing said train when it has reached a certain point in the stretch from affecting the signal; a west-bound signal; and means operable by an east-bound train when in the stretch west 80 of said west-bound signal for causing it to indicate stop.
- 85 28. In combination, a stretch of track; an east-bound signal; a control circuit for the signal; means operable by a west-bound train in any part of the stretch for opening the control circuit and thereby causing the signal to indicate stop; a normally-energized polar relay; means controlled by an east-bound train when it has reached a certain point in the stretch for operating the polar 90 relay and closing the control circuit and thereby preventing said train when it has reached a certain point in the stretch from causing the signal to indicate stop; a west-bound signal; and means operable by an east-bound train when in the stretch west 95 of said west-bound signal for causing it to indicate stop.
- 100 29. In combination, a stretch of track; an east-bound signal; a control circuit for the east-bound signal; means operable by a west-bound train in any part of the stretch for opening said circuit and causing the signal to indicate stop; an east-bound normally-energized polar relay; means controlled by an east-bound train when it has reached a certain point in the stretch for operating said polar relay and closing said 105 control circuit and thereby preventing the train when it has reached a certain point in the stretch from causing the east-bound signal to indicate stop; a west-bound signal; a control circuit for the west-bound signal; means operable by an east-bound train in 110 any part of the stretch west of the west-bound signal for opening its control circuit and causing the west-bound signal to indicate stop; a west-bound polar relay; and means operable by an east-bound train in 115 any part of the stretch west of the west-bound signal for opening its control circuit and causing the west-bound signal to indicate stop; a west-bound polar relay; and means controlled by a west-bound train when it has reached a certain point in the stretch for operating said west-bound polar relay and closing the control circuit of the west-bound signal and thereby preventing said 120 west-bound train when it has reached a certain point in the stretch from causing the west-bound signal to indicate stop.
- 125 30. In combination, a stretch of track comprising two track zones; a signal; track circuits for said track zones; means con- 130

trolled by the track circuits when operated by a west-bound train for causing the signal to indicate stop; said means being also controlled by a track circuit of the west track zone when operated by an east-bound train for causing said signal to indicate stop; and a normally-energized polar relay controlled by a track circuit operated by said east-bound train when it has reached a certain point in the stretch to prevent said train when in the east track zone from causing the signal to indicate stop.

31. In combination, a stretch of track comprising east and west track zones; two east-bound signals; a control relay for each signal, of which the westerly relay is controlled by the easterly relay; means controlled by a train in the west track zone for operating the westerly relay to cause the westerly signal to indicate stop; means controlled by a west-bound train in the east track zone for operating both of said control relays to cause both signals to indicate stop; an east-bound normally-energized polar relay controlling the westerly control relay; means controlled by an east-bound train when it has reached a certain point in the stretch for operating said polar relay and thereby preventing said east-bound train when it has reached a certain point in the stretch from causing the westerly east-bound signal to indicate stop; a west-bound signal; and means operable by an east-bound train when in any part of the stretch west of said west-bound signal for causing said signal to indicate stop.

32. In combination, a stretch of track comprising east and west track zones; two east-bound signals; a control relay for each signal, of which the westerly relay is controlled by the easterly relay; means controlled by a train in the west track zone for operating the westerly relay to cause the westerly signal to indicate stop; means controlled by a west-bound train in the east track zone for operating both of said control relays to cause both signals to indicate stop; an east-bound normally-energized polar relay controlling the westerly control relay; and means controlled by an east-bound train when it has reached a certain point in the stretch for operating said polar relay and thereby preventing said east-bound train when it has reached a certain point in the stretch from causing the westerly east-bound signal to indicate stop.

33. In combination, a stretch of track comprising east and west track zones; two east-bound signals; track circuits for the track zones, the westerly of said signals being normally controlled by the track circuits of both track zones, and the easterly of said signals being controlled by the track circuit or circuits of the east track zone; a normally-energized polar relay; means for operating

the polar relay by the action of an east-bound train when it has reached a certain point in the stretch to remove the control of said westerly signal from the track circuit or track circuits of said east track zone; and a west-bound signal controlled by the track circuits of the stretch west of said west-bound signal.

34. In a signaling system, the combination of a stretch of track; a signal; a control circuit for said signal arranged when closed to cause the signal to give one indication and when open to give another indication; a single relay having neutral and polar contacts in said circuit; means operable by an east-bound train when it has reached a certain point in said stretch for closing said circuit at one of said contacts; and means operable by a west-bound train when it has reached a point farther east in said stretch for opening said circuit at the other of said contacts.

35. In a signaling system, the combination of a stretch of track; a signal; a control circuit for said signal arranged when closed to cause the signal to give one indication and when open to give another indication; neutral and polar contacts in said circuit; means operable by an east-bound train when it has reached a certain point in said stretch for closing said circuit at one of said contacts; and means operable by a west-bound train when it has reached a point farther east in said stretch for opening said circuit at the other of said contacts, both of said means including a single magnet operating directly upon said neutral and polar contacts.

36. In combination, a stretch of track including two adjoining east and west track zones; a signal; a control circuit therefor arranged when open to cause the signal to give one indication and when closed to give another indication; a single relay having neutral and polar contacts in said circuit; means operable by an east-bound train in the west track zone for opening said circuit; means operable by the east-bound train when it has reached a certain point intermediate the stretch for closing said circuit at its polar contact; and means operable by a west-bound train in the east track zone for opening said circuit at its neutral contact.

37. In combination, a stretch of track including two adjoining east and west track zones; a signal; a control circuit therefor arranged when open to cause the signal to give one indication and when closed to give another indication; a single relay having neutral and polar contacts in said circuit, the polar contact being in a branch around the former contact; means operable by an east-bound train in the west track zone for opening said circuit; means operable by the east-bound train when it has reached a cer-

tain point intermediate the stretch for closing said circuit at its polar contact; and means operable by a west-bound train in the east track zone for opening said circuit 5 at its neutral contact, said last two means including a magnet governing said neutral and polar contacts.

38. In a signaling system, a stretch of track comprising adjoining east and west track zones; a signal; track relays and sources of current for the track zones; two control circuits for the said signal controlled by said track relays and relayed together from east to west so that when a track relay 10 of the east track zone is deenergized by a west-bound train both control circuits are opened to cause the signal to indicate stop; a single relay having a polar contact in the west control circuit; and means operable 15 by an east-bound train when it has reached a certain point intermediate the stretch for operating said polar contact and thereby preventing said train when in the east track zone from causing the signal to indicate 20 stop. 25

39. In a signaling system, a stretch of track comprising adjoining east and west track zones; a signal; track relays and sources of current for the track zones; two control circuits for the said signal controlled by said track relays and relayed together from east to west so that when a track relay 30 of the east track zone is deenergized by a west-bound train both control circuits are opened to cause the signal to indicate stop; a single relay having a neutral contact in the west control circuit through which the control circuits are relayed and a polar contact in the west control circuit in a branch around said neutral contact; and means operable 35 by an east-bound train when it has reached a certain point intermediate the stretch for operating said polar contact and thereby preventing said train when in the east track zone from causing the signal to 40 indicate stop. 45

This specification signed this 13th day of April, A. D. 1917.

ROBERT J. HEWETT.
